DISPENSING TOP FOR CONTAINERS

William G. Bursnall, Norfolk, Va.

Application September 28, 1937, Serial No. 166,179

4 Claims. (Cl. 221—106)

This invention is a device for dispensing measured quantities of powdered material.

One of the objects of the invention is to provide an attachment for containers, so constructed and arranged as to controllably discharge definitely measured quantities of the contents of the latter in a sanitary manner and without waste. A further object is to provide a dispensing device constructed of stamped metal parts which may be readily assembled and attached to the body of a suitable container, and having a rotatively mounted dispensing member controlling the discharge therefrom, said dispensing member including a measuring chamber of predetermined size. A further object is to provide a dispensing device of the character mentioned having means normally functioning to maintain the dispensing member in a closed position with the measuring chamber in position to receive a charge, and to prevent accidental discharge of the contents of the container. A further object is to provide a hopper-like member normally positioned to close and communicate with the interior of a container, and carrying a rotatively mounted dispensing member which is yieldably movable to a discharging position, and means acting to automatically return it to a normal closed position.

The invention will be hereinafter fully set forth and particularly pointed out in the claims.

In the accompanying drawing:

Figures 1 and 2 are side elevations at right angles to each other illustrating a container equipped with a dispensing device constructed in accordance with the invention. Figure 3 is a top plan view. Figure 4 is a longitudinal sectional view on the line 4—4, Figure 1. Figure 5 is a vertical sectional view on the line 5—5 of Figure 2. Figure 6 is a detail view illustrating the actuator member.

Referring to the drawing, 10 designates a container body of any desired shape, but preferably cylindrical and constructed of sheet metal, said container having the usual annular stop rib 11. The dispensing top 12 is provided with a base portion 13 engaging the rib 11, and crimped therearound to provide a permanent connection with the container 10, after the latter has been filled. The top 12 is tapered toward the axial line of the container to provide a throat having a narrow, diametrically disposed slot 15 therein providing a discharge opening, the metal above said slot being enlarged to provide a cylindrical bearing 16 parallel with the slot and open at both ends.

Rotatably mounted within the bearing 16 is a cylindrical dispensing shell 17 formed of thin metal, having a depression in its wall shaped to provide a measuring pocket 18, which is adapted to register with the discharge opening 15. One end of the shell 17 is provided with a permanent end wall 19 of thin metal, having a flange 20, which bears against the adjacent end of the bearing 16. The other end of the shell 17 is closed by a thin metal wall 21 secured to said shell, and provided with a central boss 22, around which a portion of the coil spring 23 is wound. An actuator member 25 also constructed of thin metal is provided with a flange 26 having a recess 27 therein. One end of said spring 23 bears against a lug 24 projecting from the adjacent end of the bearing 16, and extending into said recess 27. The other end of the spring bears against a lug 29 located within the actuator member 25. Said actuator member is provided with a flange 28 which bears against the adjacent end of the sleeve 16. Secured to the actuator member 25 is a flange 30 carrying a thumb piece 31, which overhangs the bearing 16. Said bearing is also provided with a discharge slot 32 at right angles to the opening 15 and in position to register with said pocket 18.

It will be noted that the edges of recess 27 are so disposed as to cooperate with the stop 29 to limit rotative movement of the shell 17 in both directions. In the normal closed position, the pocket 18 registers with the opening 15 and in the other position the pocket registers with the discharge opening 32.

In practice, the top 12 is permanently secured to the container body 10 after the latter has been filled with the material which it is desired to dispense, such as tooth powder, for instance. After the top has been secured in position it is impossible to discharge the contents of the container except through the openings arranged in the bearing 16. In operation, the pocket 18 is normally maintained in register with the opening 15, so that by inverting the body the said pocket will be filled with the powdered material. By then pressing against the thumb piece 31 the shell 17 may be rotated within the bearing 16 against the tension of spring 23, a distance limited by the walls of the recess 27, which will bring the pocket in register with the discharge opening 32, whereupon the contents of the pocket will be discharged. Upon release of the pressure against the thumb piece, the spring 23 will return the shell to its normal position with the pocket in register with opening 15. It is to be

understood that the various parts may be secured together by brazing, welding or any other desired manner.

The advantages of the invention will be readily understood by those skilled in the art to which it belongs. For instance, it will be observed that a very simple and inexpensive form of dispensing top is provided, constructed from stamped sheet metal, thereby providing a cheap and simple structure. A further advantage is that the device is so constructed that it may be connected with any type of container, and while in position will permit of the ready dispensing of measured quantities of the contents of the container.

Having thus explained the nature of the invention and described an operative manner of constructing and using the same, although without attempting to set forth all of the forms in which it may be made, or all of the forms of its use, what is claimed is:

1. In a dispensing apparatus, a top member provided with a cylindrical bearing sleeve open at both ends and provided with circumferentially disposed inlet and outlet openings respectively, a sleeve-like dispensing shell rotatively mounted within said sleeve and having a radially disposed depression to provide a measuring pocket adapted to register with said openings, said shell being closed at one end and having means for closing the adjacent end of said sleeve, an end wall closing the other end of said shell, an actuator member located adjacent to the last mentioned end wall and also closing the adjacent end of said sleeve, said actuator member being secured to the last mentioned closed end wall of the shell in such manner that rotative movements may be imparted to the shell by movements of the actuator, and means located between the actuator member and said last mentioned wall of the shell for yieldingly holding the shell in such position that the measuring pocket thereof will normally be in register with said inlet opening.

2. In a dispensing apparatus, a top member provided with a cylindrical bearing sleeve open at both ends and provided with circumferentially spaced inlet and outlet openings, a sleeve-like dispensing shell of thin metal rotatively mounted within said sleeve and having a radially disposed depression to provide a measuring pocket adapted to register with said openings, one end of said sleeve being closed by an integral end wall provided with an annular flange so positioned as to close the adjacent end of said sleeve, an end wall closing the other end of said shell and located within the same, an actuator member located adjacent to the last mentioned end wall and also closing the adjacent end of said sleeve, said actuator member being secured to the last mentioned closed end wall of the shell in such manner that rotative movements may be

imparted to the shell by movements of the actuator member, and means located between the actuator member and said last mentioned end wall of the shell for yieldingly holding the shell in such position that the measuring pocket thereof will normally be in register with the inlet opening. 5

3. In a dispensing apparatus, a top member provided with a cylindrical bearing sleeve open at both ends and provided with circumferentially spaced inlet and outlet openings, a sleeve-like dispensing shell of thin metal rotatively mounted within said sleeve and having a depression therein providing a measuring pocket adapted to register with said openings, said shell being closed at one end by an integral end wall having portions of the metal bent upon itself to provide an annular flange adapted to close the adjacent end of said sleeve, a separate end wall closing the other end of said shell and secured thereto, said last mentioned end wall having an axially extended central boss, an actuator member also formed of thin metal located adjacent to said boss, said actuator member having a chamber therein adapted to enclose said boss, and a portion secured to the boss-carrying wall in such manner that said shell may be rotated by movements of the actuator member, said actuator member also closing the adjacent end of said sleeve, and a spring encircling said boss and having its ends respectively engaging said actuator member and said bearing sleeve. 20 25 30

4. In a dispensing apparatus, a top member provided with a cylindrical bearing sleeve open at both ends and provided with an inlet opening 35 and an outlet opening at circumferentially spaced positions, a sleeve-like dispensing shell of thin metal rotatively mounted within said sleeve and having a circumferential depression to provide a measuring pocket so positioned that it may be caused to selectively register with said openings, said shell being closed at one end by an integral wall having portions bent back upon themselves to provide an annular flange engaging and closing the adjacent end of the bearing sleeve, 45 a separate end wall secured within said shell contiguously to the other end thereof in such manner as to close the latter, said last mentioned end wall having an axially extended centrally disposed boss, a circular actuating member having an inturned annular flange secured to said separate end wall and of such diameter as to close the other end of said bearing sleeve, said flange having an opening to receive said boss, said flange also having an arcuate recess therein, said sleeve having a stud projecting into said recess, and a spring encircling said boss, one end of said spring engaging said sleeve and the other end thereof engaging said actuating member. 50 55 60
